UNITED STATES PATENT OFFICE.

BENTON C. ROWELL, OF BOSTON, MASSACHUSETTS, ASSIGNOR TO THE ROWELL-POTTER SAFETY STOP COMPANY, OF PORTLAND, MAINE.

SIGNAL-OPERATING SYSTEM FOR RAILWAYS.

SPECIFICATION forming part of Letters Patent No. 599,456, dated February 22, 1898.

Application filed July 6, 1896. Serial No. 598,157. (No model.)

To all whom it may concern:

Be it known that I, BENTON C. ROWELL, of Boston, in the county of Suffolk and State of Massachusetts, have invented an Improved 5 Signal-Operating System for Railways, of which the following is a specification, reference being had to the accompanying drawings, in which—

Figure 1 is a diagram showing my system 10 as a whole, the semaphore-arms being in line with the track for clearness. Figs. 2 and 3 are elevations of the semaphore connections. Fig. 4 is an elevation of the controlling apparatus. Fig. 5 is a sectional plan on line 15 5 5 of Fig. 4. Fig. 6 is an elevation of the power-storing apparatus. Fig. 7 is an elevation of the actuating mechanism of the power-storing apparatus. Fig. 8 is a partial elevation of Fig. 6. Fig. 9 is a section on line 9 9 20 of Fig. 6 in direction of arrow x. Fig. 10 is a partial section on line 10 10 of Fig. 6 in direction of arrow y.

My invention is a power signal system, one 25 feature of which is a coiled-spring power-storing apparatus in which one end of the spring is moved in storing power and the other end in expending power and in which the power is stored by a succession of impulses from a passing train.

30 A second feature is a power-storing apparatus having automatic adjustable means to regulate the amount of stored power.

A third feature of my invention is a controlling mechanism for the power-storing apparatus 35 adapted to hold and control an apparatus exerting great power and yet itself to be released by a very slight power.

In Fig. 1 of the drawings I have shown diagrammatically my system. A indicates the 40 power-storing and signal-operating apparatus; B, the controlling mechanism; b b', the electrical connections by which the controlling mechanism is operated from a distance; D, a safety-stop; D', a visual signal; E, a 45 second safety-stop so connected to the connecting mechanism as to be always opposed to safety-stop D; E', a visual signal. D' and E' are connected and in accord with D and E, respectively. It will be obvious that for 50 the safety-stops D and E and signals D' E', with which my power-storing and control-

ling apparatuses are shown as connected, any suitable and desirable mechanism which it is desired to operate—as, for example, a switch—may be substituted. The safety-stop and signal system indicated above is fully described in Letters Patent No. 556,773, dated March 24, 1896.

In Fig. 7 I show a compound lever A', adjusted beneath and in contact with the rails 60 of a railway and pivoted at a. The free end of the lever is pivotally connected to a rod a'. It is obvious that any depression of the rails will cause the long end of lever A' to move and with it rod a'. (See Figs. 6 and 9.) 65 The upper end of rod a' is pivotally connected to a lug a² upon a strap a³, which encircles and revolves upon a drum a⁴. Pawls a⁵, also pivotally connected with lug a², engage ratchet-wheels a⁶, fast to drum a⁴. 70

It will be obvious that in a power-storing apparatus which operates by a succession of impulses it is a desirable object, tending to promote the life of the mechanism, to utilize slight movements of the actuating mechanism, and these ratchet-wheels are so secured to the drum with relation to each other that the teeth upon one wheel are as far from coinciding with the teeth of either of the other wheels as is possible. In this way the length 75 80 of a tooth upon one of the ratchet-wheels is divided into as many parts as there are ratchet-wheels, and a very slight movement of the lever A' can be utilized. The same result may be reached by allowing the teeth 85 of the ratchet-wheels to coincide and securing the pawls in such a manner or varying the length of the pawls in such a manner that the length of the teeth upon the ratchet-wheels will be subdivided in the above-mentioned 90 way—that is, so that only one pawl at a time will engage a tooth of a ratchet-wheel, the other pawls being idle. The result of this arrangement or shaping of parts will be the same as that mentioned in the preceding 95 paragraph.

Within the drum are a plurality of coiled springs a⁷, fast at one end to the drum and at the other to a main shaft a⁸. The ends of shaft a⁸ are supported by standards. Part of 100 the frame of the apparatus and the drum itself turns upon shaft a⁸, the heads of the drum

a^4 being bored to allow the ends of shaft a^8 to project from the drum. It will now be obvious that movement of lever A' will, through rod a' , pawls a^5 , and ratchet-wheels a^6 , cause the drum a^4 to revolve and springs a^7 to be coiled tighter upon shaft a^8 , provided that shaft a^8 is prevented from turning and provided that drum a^4 is held in the position to which it may be pushed by pawls a^5 . Shaft a^8 is ordinarily prevented from turning, as will hereinafter be explained. Drum a^4 is prevented from moving in any other direction than that in which it is actuated by pawls a^5 by a second set of pawls a^9 , engaging ratchet-wheels a^6 . These pawls are prevented from lateral motion by a slotted lug a^{10} upon strap a^3 , and from longitudinal motion by links a^{11} , pivotally connected to the frame of the apparatus. Springs a^{12} keep pawls a^9 in engagement with ratchet-wheels a^6 . The length of the slot in the lug is sufficient to allow the greatest possible movement to strap a^3 under the influence of lever A' through the various connections. It will now be obvious that every deflection of the rails over lever A' will tighten the springs in drum a^4 . It will also be obvious that, unless provision is made against such a result, it would be possible for the springs to become too tightly wound upon shaft a^8 , and thus broken. I prevent this result by automatic mechanism which, when the springs have been wound as tightly as is deemed desirable, catches the rod a' upon its upward movement and holds it in this inoperative position until the springs have been uncoiled to a certain extent, when the rod a' is released and falls, and the lever A' is thus once more brought into operation. It will be apparent that this automatic regulating feature is a matter of much practical importance in a power-storing apparatus such as I have described, inasmuch as without it it would be possible to greatly strain or break the mechanism after a proper limit of stored power had been reached. This automatic regulating mechanism, as shown, consists of a shaft a^{13} , parallel with the main shaft a^8 and supported at either end in bearings a^{14} . Longitudinal movement of shaft a^{13} is prevented by collars a^{15} and by the hub of spur-gear a^{16} . Spur-gear a^{16} meshes with spur-gear a^{17} , fast to shaft a^8 . Shaft a^{13} is screw-threaded for a part of its length, the screw-threads being marked a^{18} , and a traveler spur-gear a^{19} , having an interiorly-screw-threaded hub, is mounted upon the shaft upon this screw-threaded portion and engages the teeth of a toothed cylinder a^{20} , which is secured upon drum a^4 . (See Figs. 6 and 10.) It will be obvious that if shaft a^8 revolves shaft a^{13} will revolve in the opposite direction and spur-gear a^{19} will be moved in one direction along shaft a^{13} by means of the screw-threads on the shaft and the screw-threaded hub, spur-gear a^{19} not itself revolving, being in mesh with toothed cylinder a^{20} , fast to drum a^4 . If, however, the drum a^4 is revolved, traveler-

gear a^{19} will be revolved in the opposite direction and will move along shaft a^{13} in a direction opposite to that in which it moved before. 70

It will be plain now that revolution of the drum a^4 , which winds the coiled springs a^7 and thus stores up power, will cause the traveler-gear a^{19} to move longitudinally upon shaft a^{13} in one direction, while movement of main shaft a^8 , which is the power-expending motion of the apparatus, will cause the traveler-gear a^{19} to move in the opposite direction. It is only necessary, therefore, to supply mechanism by means of which this longitudinal motion of traveler-gear a^{19} may be utilized to hang up or release rod a' , as the case may be, and so proportion the gears $a^{16} a^{17}$ and gear a^{19} and toothed cylinder a^{20} that the required revolution of shaft a^8 and drum a^4 may give 85 sufficient longitudinal movement to traveler-gear a^{19} . It will be obvious that this double capacity of the traveler-gear a^{19} to receive motion either from shaft a^8 or from toothed cylinder a^{20} is essential to proper regulation of 90 a power-storing machine, the parts of which move only in one direction and which is capable from its construction of both storing and expending power at the same instant, for by means of this double capacity of the traveler-gear if the storage and expenditure of power is proceeding at the same rate of speed there is no movement of the traveler-gear, the tendency of traveler-gear a^{19} to move in one direction as shaft a^{13} revolves being neutralized by 100 its tendency to move in the other direction as it is itself revolved by toothed cylinder a^{20} , and the simultaneous storage and expenditure of power always has the effect of either causing the traveler-gear to remain at the 105 same point upon shaft a^{13} or more or less retarding its movement in one direction or the other as the storage and expenditure of power vary in their relation to one another. The longitudinal movement of traveler-gear a^{19} is 110 utilized by means of a forked arm a^{21} , which swings upon a shaft a^{23} , (see Figs. 6 and 10,) the forks of the arm being upon opposite sides of gear a^{19} . This arm is loosely connected by a pin a^{22} to a disk a^{24} , the pin working in a 115 slot in the disk. The disk is controlled by a spring-rod a^{25} , one end of which reciprocates in a bearing a^{26} , which serves also as an abutment for spring a^{27} , and the other end of which is pinned to the disk. A bolt a^{28} , reciprocating 120 in a bearing a^{29} , lies next to the disk and a pin a^{30} in the disk enters a slot in this bolt. The bolt a^{28} has a tooth across its face. Upon that side of rod a' opposite this toothed face of bolt a^{28} is a ratchet the teeth of which are 125 not more in size than the smallest movement of rod a' , which pawls a^5 and ratchets a^6 will utilize. This relation of size is necessary, as otherwise after rod a' had been caught by bolt a^{28} and hung up the passage of a wheel a little heavier or faster than that which actuated rod a' when it was caught and hung up would actuate the rod slightly and drum a^4 might be revolved without rod a' being caught itself at 130

a higher point, and thus it would be possible to go on revolving the drum after the springs were tightly coiled.

The operation of the power-storing apparatus is as follows: The machine being set in position and, say, half-stored, the traveler-gear a^{19} is at the position shown in Fig. 6. The passage of a train will actuate levers A' and will, through rod a', pawls a⁵, and ratchet-wheels a⁶, revolve drum a⁴ and wind up springs a⁷. This motion of drum a⁴ will revolve traveler-gear a¹⁹, through toothed cylinder a²⁰, fast to drum a⁴, and will cause gear a¹⁹ to move to the left upon shaft a¹³. This movement will turn disk a²⁴, through arm a²¹, until spring-rod a²⁵ is at a dead-center. Any further movement of the disk will leave spring a²⁷ free to operate, and the disk will be thrown around until stopped by the end of the slot in the disk and the pin a²² on forked arm a²¹. This movement of the disk will shoot bolt a²⁸ forward through pin a²⁹, fast to the disk and working in a slot in bolt a²⁸, and thus engage tooth on bolt a²⁸ with the ratchet on rod a'. Until bolt a²⁸ is withdrawn spring a²⁷ tends constantly to keep it pressed forward. Movement of shaft a⁸ will reverse this process. Shaft a¹³ revolving within the hub of traveler-gear a¹⁹ and forcing gear a¹⁹ to the right until the disk is thrown over by spring a²⁷ and bolt a²⁸ is withdrawn from engagement with the ratchet on rod a'. Shaft a⁸ is connected with the work to be done in any suitable manner. As the work to be done (shown in the drawings) is the setting of safety-stops and signals, the connecting-rod F of the safety-stops is connected to shaft a⁸ by means of a link f and a crank upon the end of shaft a⁸. (See Figs. 1 and 8.) As has been explained, every onward movement of drum a⁴ is held by holder-pawls a⁹. So far as appears there is no reason why shaft a⁸ should not revolve and allow springs a⁷ to uncoil as fast as springs a⁴ are coiled by the revolution of drum a⁴. This is provided for by my controlling mechanism, which I will now describe.

It will be obvious that one-half a revolution of a shaft a⁸ would throw connecting-rod F in one direction, while the balance of the revolution would throw rod F back to its original position and therefore would undo the work just performed. It is necessary, therefore, that at the end of one-half a revolution the shaft a⁸ should be stopped and held until it is desired to reverse the position of the signals or the like controlled by rod F. This is accomplished by the mechanism shown in Figs. 4 and 5. This mechanism is in effect two machines, each of which controls the movement of rod F in one direction. In Figs. 1 and 4 rod F is shown thrown over as far as it can go to the left. Upon the entrance of a train into the section protected by safety-stops D E and signals D' E', which would be from the left of Fig. 1, the section being clear, the train passes over safety-stop E and

before reaching safety-stop D closes the circuit b, drawing the armature b², connected with that circuit, and releasing lever b³. Spring b⁴ on spring-rod b⁵, pinned at its upper end to lever b³, immediately lifts b³, carrying pin b⁶ out of the path of arm b⁷ on rock-shaft b⁸. Through link b⁹ spring b⁴ now tends to pull arm b⁷ forward, while rod F, through ratchet-teeth f', pawl b¹⁰, and arm b¹¹ on rock-shaft b⁸, pushes it forward, the effort of the power-storing apparatus A being to move rod F to the right. As pawl b¹⁰ is moved to the right by rod F it encounters stud b¹² and is lifted out of engagement with ratchet-teeth f'. Rod F, released from control, is thrown by power apparatus A to the right, bringing ratchet-teeth f' at the left of the drawings into engagement with pawl b¹⁰ at the left of the drawings, thus preventing any further motion of shaft a⁸. The resetting of the mechanism is accomplished as follows: Standard b¹³, fast to rod F, carries at its upper end a bearing b¹⁴ for spring-rod b¹⁵, b¹⁴ being also an abutment for the spring b¹⁶. Standard b¹³ also carries a pin b¹⁷, which works in a cam-slot in lever b¹⁸, which is fulcrumed at b¹⁹ to the frame of the machine. One end of spring-rod b¹⁵ is pinned to arm b⁷ and one end of lever b¹⁸ serves as a bearing for spring-rod b⁵ and an abutment for spring b⁴. It will be apparent that as soon as rod F moves to the right spring b¹⁶ will be compressed, first, because arm b⁷ pulls spring-rod b¹⁵ to the left, and, secondly, because bearing b¹⁴ pushes spring b¹⁶ to the right. As soon, therefore, as pawl b¹⁰ is freed from teeth f' arm b⁷ will return to its upright position. The movement of standard b¹³ to the right also operates the cam-lever b¹⁸, raising the end at the right of Fig. 4 and, through spring-rod b⁵, drawing lever b³ down, so that it may be caught by the detent of the armature b². At the end of the stroke of rod F to the right the position of the parts will be as shown in the duplicate mechanism at left of Fig. 4. Lever b¹⁸ will hold lever b³ down, through spring-rod b⁵, until cam-lever b¹⁸ is reversely operated by the movement of rod F, when the parts to the right of Fig. 4 will again be as shown, spring b⁴ compressed and spring-rod b⁵ free to move up when lever b³ is released. As the train leaves the section thus blocked the circuit b' is closed and its armature released, when the duplicate mechanism shown at the left of Fig. 4 operates as above described, except that it permits a half-revolution of shaft a⁸ and a consequent motion of rod F from right to left, thereby unblocking the section, for the motion of rod F from left to right sets safety-stop E and semaphore E' to "danger" and stop D and semaphore D' to "safety" by the connections shown in Figs. 1, 2, and 3 and as fully described in my patent above referred to, while the reverse motion of rod F sets them as in Fig. 1.

What I claim is—

1. In a signal-operating system, the com-

bination of a main shaft; a drum mounted upon that shaft; a coiled spring connecting the drum and the shaft; means to rotate the drum continuously in one direction by a succession of impulses from a passing train; means to prevent the drum from rotating in the opposite direction and means to prevent the rotation of the main shaft until the power of the apparatus is to be expended, substantially as described.

2. In combination a main shaft; a drum mounted upon that shaft; a coiled spring connecting the drum and the shaft; means to rotate the drum continuously in one direction by a succession of impulses from a passing train; and means to prevent the drum from rotating in the opposite direction, substantially as described.

3. In combination a coiled-spring power-storing apparatus, made up of a drum mounted upon a main shaft and the two connected by a coiled spring; a toothed cylinder upon

the drum; a traveler-gear having an internally-threaded hub and in mesh with the toothed cylinder; a screw-threaded shaft upon 25 which the traveler-gear is mounted; and means to connect the main shaft and the screw-threaded shaft, all organized so that movement of the main shaft will cause the traveler-gear to travel in one direction along 30 the screw-threaded shaft while movement of the drum in the same direction as the main shaft will cause the traveler-gear to move along the screw-threaded shaft in a direction opposite to its former movement.

4. In a power-signal system a controlling apparatus consisting of detent b^2 ; a lever b^3 ; spring b^4 tending to lift lever b^3 ; pin b^6 ; lever b^7 , rock-shaft b^8 ; lever b^{11} ; and pawl b^{10} all organized and operating as described. 35
